UNITED STATES PATENT OFFICE.

CHARLES E. THOMPSON, OF TROY, NEW YORK, ASSIGNOR OF ONE-HALF TO FRANCIS H. WAGER, OF TROY, NEW YORK.

TOOTH-BRUSH.

1,209,516.

Specification of Letters Patent. Patented Dec. 19, 1916.

Application filed October 19, 1915. Serial No. 56,671.

To all whom it may concern:

Be it known that I, CHARLES E. THOMPSON, a citizen of the United States of America, residing at the city of Troy, in the 5 county of Rensselaer and State of New York, have invented certain new and useful Improvements in Tooth-Brushes, of which the following is a specification.

My invention relates to tooth brushes, and 10 the object of my invention is to provide a tooth brush made up of short, strong, elastic, projecting prongs which will be efficacious, pleasant and durable in use; together with such other elements and combinations as are hereinafter more particularly set forth and claimed.

I accomplish these objects by means of the mechanism illustrated in the accompanying drawing, in which:

20 Figure 1 is a plan view partly in section. Fig. 2 is a longitudinal section along the lines, 1—1, on Fig. 1. Fig. 3 is a perspective view with a part of the handle broken away.

25 Similar letters refer to similar parts throughout the several views.

On a suitable handle, A, I place a tube, B, which tube is closed at one end, C, provided with a contracted portion, D, at the other 30 end which is open and into which the supporting end of the handle, A, may be inserted, as shown in Figs. 1 and 2. I make the inner side, b, of the tube, B, parallel with with the other walls surrounding the cavity 35 lengthwise, but concave on its outside or face from which the prongs, E, project. There will thus be secured a graduated increase of thickness of rubber in the body face from the center of the brush lengthwise 40 toward each end with a maximum thickness at the ends. This is clearly seen in Fig. 2.

I construct the prongs, E, relatively large at the bottom and coming to a point or edge at the top, preferably wedge or chisel-shaped, so that the diameter of the base portion shall be approximately half the length 45 of the prongs. It is important to avoid too great length of prong, since by increasing the pivoting arc of each prong, just so much 50 reduces the friction produced by the general movement of the brush, and it is friction alone that cleanses the teeth and gums during the process of brushing. Prongs $\frac{1}{2}$ in. long will pivot $\frac{1}{8}$ in. each way without friction. If, therefore, there is a 1-in. stroke the

friction stroke is only $\frac{1}{4}$ in., and if, as frequently happens, the tooth brush stroke is only $\frac{1}{4}$ in., there is no friction stroke at all. This has been shown to be a fact. The $\frac{1}{4}$ in. prong under the same conditions would have 60 a play each way of $\frac{1}{16}$ in., which theoretically would cause only $\frac{3}{8}$ in. loss of friction, but in reality it would be less, since the farther the prong extends from the back of the brush, the more readily it bends under 65 pressure. The prongs should be, when made of rubber or similar material, about or approximately $\frac{1}{4}$ in. in length. They should be wedge, or chisel shaped and at the base they should be about $\frac{1}{8}$ in. in diameter. 70 When they are made as heretofore constructed—long and conically-shaped truncated prongs—they bend, as before stated, without giving sufficient friction in the stroke of the brush through the mouth; they will 75 not enter between the teeth and dislodge the particles and are very ineffectual in operation. A perfect cone-shaped prong is preferable to a truncated-cone form, or a blunt-ended slightly tapering prong, but a wedge-shaped prong is the most efficient form 80 of all.

In order to have the particles which have become lodged between the teeth removed, it is necessary that the prongs should be inserted between the teeth. To do this they must be of such form as will permit them to enter the cavities or interstices, and they must also have stiffness which will cause 85 them to project therein. 90

When I have used the term "rubber," I mean to include any similar pliable material.

The principle of construction in the formation of a rubber tooth brush, for which I contend and for which I ask the protection 95 of United States Letters Patent, is that of a body with prongs integral thereof, having their bases relatively wide in proportion to their length, and having their outer ends terminating in chisel shapes. In other words, in wedge form, so that the juxtaposition of their bases prevents the too close proximity of their outer ends, thereby preventing the overlapping of the ends in operation and permitting the effectual action 100 and complete function of each separate prong and assuring both abrading and penetrating action of all the teeth. To correctly correlate tooth action with tooth form positively, requires that the latter be such as to 105 110

fix a practical efficient mean between stiffness and flexibility. This result is brought about in a high degree by the kind of a tooth which I have described.

5. What I claim as my invention and desire to secure by Letters Patent is:

1. A rubber tooth brush having a series of acute angle, triangular, prism-shaped prongs arranged in rows running lengthwise of the body thereof, and having their flat, tapering sides set transversely thereto.

10. 2. A tooth brush comprising a handle; a rubber tube having at one end a restricted neck, one of the walls of the cavity through the tube straight and parallel to the axis of the tube on the inner side and concave on the outer side; and a series of prongs on the said concave surface of the tube, said prongs sharpened at one end and differing in diameter gradually from their base to the sharpened end, substantially as described.

15. 3. A rubber tooth brush having a longitudinal cavity in its body adapted to receive the end of a supporting handle and having 20 one of the walls of the cavity straight parallel to the axis of the tubular body on its

inner side and concave on its outer side, said concave side having a series of wedge-shaped prongs projecting therefrom, substantially as described.

30

4. A hollow-bodied rubber tooth brush having wedge-shaped prongs integral with the body thereof and projecting from a concaved face, having its inner surface a plane parallel with the upper or opposite wall of 35 the chamber, or hollow interior of the brush body.

5. A rubber tooth brush having a longitudinal chamber in its body, and provided with two or more rows of acute angle, triangular, 40 prism-shaped prongs running lengthwise, with their flat sides set crosswise of, and projecting from one side of the brush body and being integral therewith, combined with a handle having its supporting end inserted 45 in the chamber in the brush body.

In testimony whereof I have affixed my signature in presence of two witnesses.

CHARLES E. THOMPSON.

Witnesses:

BEULAH CARLE,

FREDERICK W. CAMERON.
